DUPLICATING APPARATUS

Alfred Marchev, La Grange, Ill., assignor to Ditto,
Incorporated, Chicago, Ill., a corporation of
West Virginia

Application March 9, 1940, Serial No. 323,164

15 Claims. (Cl. 101—132.5)

This invention relates to duplicating apparatus and particularly to duplicating machines of the liquid process type in which a master sheet bearing subject matter written or otherwise produced in reverse by the use of copy ink is carried around by a drum so as to be brought into impression relationship with copy sheets one at a time, each of such copy sheets being provided in turn with a film of solvent on its face so as to be brought into engagement with the ink of the master sheet for producing a positive copy of the subject matter on the copy sheet. It is the object of this invention to provide in a machine of this type a new and improved form and arrangement of parts by which improved results may be attained by the use of a simple construction which is easy and inexpensive to manufacture and assemble.

This application discloses a new and improved form of moistening means for the application of a film of solvent to one of a pair of forwarding rollers for transfer of the film to the face of a copy sheet moved forwardly by the rollers into the grip of the drum and its cooperating impression roller forming a part of the machine, but such improved moistening means is not claimed herein, since the same is disclosed and claimed by a co-pending application Serial No. 323,165, filed March 9, 1940.

In the arrangement illustrated herein, an improved form of feeding and forwarding means for the copy sheets is shown, adapted to deliver copy sheets one at a time to the grip of the drum and the impression roller cooperating therewith, and comprising an intermittently driven feed roller which carries the top one of a pile of sheets into the bite of a pair of intermittently driven forwarding rollers which in turn, carry the sheet forwardly into the bite of the drum and impression roller. In this construction, the power is applied to the feed roller and to the forwarding rollers for driving them intermittently by means of clutch devices which drive in one direction only for forwarding a copy sheet and which yield for permitting the copy sheet to be drawn forwardly by the drum independently of the normal driving means when the copy sheet is brought into operative engagement with the drum. In the preferred construction, the means for actuating the feed roller and the forwarding rollers comprises an operating arm which is swingingly mounted in position and which is given an operative stroke in one direction for rotating the feed roller in the desired timed relation to the rotation of the drum for feeding a copy sheet

forwardly from the pile of sheets into the bite of the forwarding rollers, and which is given a quick motion operative stroke in the opposite direction for rotating the forwarding rollers in the direction for advancing the copy sheet from the feed roller into the bite of the drum and co-operating impression roller. In the arrangement shown, the operating arm is actuated for driving the feed roller by means of a cam and is actuated in the opposite direction for driving the forwarding rollers by means of a coiled spring which acts under the control of said cam.

For providing the desired adjustment and control of the size of the margin at the top of the copy sheet above the printed matter thereon, means is included for adjusting the position of the actuating cam with respect to the driving means therefor, which is actuated in timed relation to the rotation of the drum. By adjusting the position of the cam, it is made to act at any desired point in the revolution of the drum so as to control the position of the copy sheet with respect to the master sheet. Indicating means is also provided for showing the position of the cam so as to expedite the adjustment of the parts to the desired position.

Improved means is provided for mounting the drum rotatably in position in the framework, comprising radially disposed channel portions in the side frame members of the machine arranged to receive bearing members carried by the drum on its end faces, with removable pins or screws securing the drum in position, the arrangement being such that the drum can be very quickly and easily mounted in its operative position or removed from operative position.

It is one of the objects of this invention to provide an improved arrangement of supporting means for a pile of copy sheets to be fed into the machine, together with an improved arrangement of adjustable margin bars and adjustable side pressure parts for controlling the withdrawal of the copy sheets one at a time for delivery to the drum.

The improved machine comprises further a new arrangement of means for securing a master sheet releasably in position on the drum, together with an improved arrangement of means for clamping and unclamping the master sheet. The means shown for clamping the master sheet in position on the drum comprises a light flexible bar mounted loosely in the groove in the drum into which the leading edge of the master sheet is inserted, together with spring pressed fingers which bear on the bar and press it tightly against

the end of the master sheet. Means is provided for opening the gripping mechanism, comprising a trip member pivotally mounted on the frame adapted to be moved manually into position for engagement with an arm carried by the drum and movable with the spring pressed fingers by which the flexible bar is pressed into holding engagement with the master sheet, the arrangement being such that upon operative engagement of said arm with said trip member under pressure 10 conditions the fingers are actuated against the pressure of the associated spring means for relieving the pressure of the flexible bar against the end of the master sheet.

It is another object of this invention to improve mechanisms of this type in sundry details hereinafter pointed out. The preferred means by which the several objects have been attained are illustrated in the accompanying drawings, in which—

Fig. 1 is a side view of the improved machine as seen from the right in Fig. 2 but with the side closure plate and the crank handle removed;

Fig. 2 is a top plan view of the improved machine with parts broken away for clearness of 25 illustration;

Fig. 3 is a longitudinal vertical sectional view taken substantially at the line 3—3 of Fig. 2;

Fig. 4 is a detail view similar to a portion of Fig. 3 but upon a considerably enlarged scale;

Fig. 5 is an enlarged view of a portion of the structure as shown in Fig. 1 but with a supporting plate member and other parts removed and with some of the parts broken away;

Fig. 5a is a view similar to a portion of Fig. 5 35 but with an operating arm and its actuating parts in changed position;

Fig. 6 is a sectional view taken substantially at the line 6—6 of Fig. 5;

Fig. 7 is a view similar to Fig. 5 but with a 40 heavy operating arm and other parts removed and with some parts partially broken away;

Fig. 8 is a side face view of a fragmentary portion of the machine substantially as seen at the line 8—8 of Fig. 2;

Fig. 9 is a view similar to a portion of Fig. 7 but with a more complete showing of the side plate of the machine frame and of the operating means for controlling the clamping mechanism for a master sheet, and with some of the operating parts in changed position as compared with the showing of Fig. 5;

Fig. 10 is a rear face view of the feed roller for copy sheets, together with the mounting means for said roller, being in part a vertical section 55 taken substantially at the line 10—10 of Fig. 7;

Fig. 11 is a vertical sectional view taken substantially at the line 11—11 of Fig. 7;

Fig. 12 is a vertical sectional view taken substantially at the line 12—12 of Fig. 8;

Fig. 13 is a sectional view taken substantially at the line 13—13 of Fig. 9;

Fig. 14 is a top plan view of a fragmentary portion of the drum and the adjacent parts with the groove for the master sheet positioned at the 65 top and with a portion of the side frame member broken away for better showing the parts;

Fig. 15 is a similar view with some of the parts removed and with a portion of the drum broken away;

Fig. 16 is a vertical sectional view taken substantially at the line 16—16 of Fig. 14, but with the end plate of the drum removed;

Fig. 17 is a vertical sectional view taken substantially at the line 17—17 of Fig. 15; and

Fig. 18 is a fragmentary sectional view taken substantially at the line 18—18 of Fig. 7.

Referring now to the several figures of the drawings, in which corresponding parts are indicated by the same reference characters, 25 and 26 indicate side plates comprising the major members of the framework of the machine, each of said side plates being provided with an outwardly directed flange 27 thereabout, as is best shown in Fig. 1. The side plates 25 and 26 are rigidly connected together by means of cross bars 28 and 29 (see Fig. 3) and by a transversely extending frame plate in the form of an angle comprising a vertically disposed portion 30 and a horizontally disposed portion 31, as is shown in said Fig. 3. Each of the side plates 25 and 26 is provided with a radially extending channel portion 32 comprising connecting flanges 33 and 34, as is best shown in Fig. 9, each of said channels opening inwardly, as is best indicated in Fig. 6. Between the side plates 25 and 26, a drum 35 is mounted, such drum in the arrangement shown comprising end plates 36 and a cylindrical wall portion 37. The cylindrical wall portion 37 is in the form of a casting, (see Fig. 3) having strengthening ribs 38 thereon. The drum at opposite ends is provided with bearing members 39 which are slidable along the channels 32 of the side plates when the drum is moved into position in the framework. The bearing 39 at the near side of the machine as shown in Fig. 2 is provided with a pinion 40 for applying power to the drum for rotating it as hereinafter described. The drum is mounted in position between the side plates 25 and 26 by means of pins or screws 41. As is best shown in Fig. 5, a second pinion 42 rotatably mounted upon the framework in position to mesh with the pinion 40 is provided for driving the drum as hereinafter described. The pinion 42 is in position at one side of the path of the pinion 40 into and out of its operative position so as to provide clearance for the movement of the pinion 40 along the channels 32. By the provision of this arrangement, the drum can be very quickly and easily moved into and out of operative position in the framework.

In the form of machine as illustrated, end closure plates 43 and 44 are secured in position substantially coextensive with the side plates 25 and 26 respectively, as is best shown in Fig. 2.

At one side of the drum, it is provided with an outwardly open groove 45 cut in the cylindrical wall portion 37 adjacent to one of the strengthening ribs 38, as is best shown in Fig. 17. Within this groove, a bar 46 is loosely mounted, being held in position by longitudinally extending lugs 47 carried by the end plates 36 of the drum, as is clearly shown in Fig. 18, the lugs 47 being in engagement with notches 48 in the ends of the bar. In the arrangement shown, the bar 46 is in the form of a light thin flexible strip of metal, being of such width as to cause its outer edge to be substantially flush with the cylindrical face of the drum. The arrangement is such that the bar 46 is adapted to be pressed into holding engagement with the end of a master sheet 49 inserted in the groove so as to hold the master sheet strongly in position on the drum.

The means employed for pressing the bar 46 against the face of the groove 45 comprises a rock shaft 50 rotatably mounted between the end plates 36 of the drum adjacent to the groove, such rock shaft being provided with fingers 51

mounted thereon in spaced relation to each other along the shaft. Each of the fingers 51 is normally pressed lightly in clockwise direction with respect to the shaft 50, as shown in Fig. 17, by means of coiled springs 52 which bear on the shaft and on the several fingers. At the near side of the machine as shown in Fig. 1, the shaft 50 is provided with an arm 53 which extends inwardly from the shaft, such arm 53 being normally pulled toward the left in Fig. 16 by means of a coiled spring 54 so as normally to cause the fingers 51 to press the bar 46 into gripping relationship to the face of the groove 45. As is best shown in Figs. 15 and 16, the inner end of the arm 53 is turned at right angles to provide a longitudinally extending lug 55 for purposes hereinafter brought out.

A platen roller 56 is mounted below the drum 35 by means of a shaft 57 which is rotatably mounted in supporting plates 58 pivotally mounted by means of machine screws 59 on the outer faces of the side plates 25 and 26 respectively of the machine. At their forward ends the plates 58 are provided with set screws 60 which bear upon cams 61 rotatably mounted in position by means of a shaft 62 which extends outwardly beyond the end closure plate 44, as is clearly shown in Fig. 2, being provided with a head 63 on its outer end for ready manipulation of the shaft. The arrangement is such that by rotary movement of the shaft 62 and the cams 61 the supporting plates 58 can be swung about the pivot pins 59 for controlling the degree of pressure of the platen or impression roller 56 against the face of the drum 35.

At the rear end of the machine, a table 64 is mounted in position for supporting a pile of copy sheets 65 for delivery one at a time to the drum 35. The table in the arrangement shown is in the form of a sheet of metal having a downwardly turned flange 66 at its front end and flanges 67 at its side edges for providing the required strength. The table is pivotally mounted at its outer edge portion by means of machine screws 68 passing through the flanges 67 and through rearwardly extending arms 69 carried by the frame of the machine, as is clearly shown in Figs. 2 and 3. Above the front edge of the table 64, a feed roller 70 is provided rotatably mounted in position by means of a shaft 71 as hereinafter described. Coiled springs 72 are connected at their front ends with the frame bar 28 and at their rear ends with arms 73 extending downwardly from the table adjacent to the axis of the table, such springs serving normally to hold the table swung to the limit of its motion in counterclockwise direction in Fig. 3 with the top sheet of the pile of sheets 65 pressing upwardly against the feed roller 70. The frame bar 69 at one side of the machine is provided with a pivotally mounted latch member 74 adapted by engagement with a pin 75 carried by the table to hold the table in lowered position for ready insertion of a pile of sheets in adjusted position upon the table 64.

Means is provided in connection with the table 64 for controlling the position of a pile of sheets on the table, such means comprising margin bars 76 at opposite sides of the table, each in the form of an angle, as is best indicated in Fig. 2. These margin bars are held adjustably in position with respect to the table 64 by means of screw devices 77 which extend through transversely positioned slots 78 in the table and through outwardly extending lugs 79 carried by

the margin bars. At their inner edges, the bars 76 are provided with downwardly turned lugs 80 which engage the slots 78 for assisting in holding the margin bars in operative position on the table.

Each of the margin bars 76 is provided with a pressure pad adapted to engage the adjacent side face of a pile of sheets mounted on the table. In the construction illustrated, such pressure pads are in the form of blocks 81 of sponge rubber carried on the inner faces of spring brackets 82 mounted on the outer faces of the bars 76, the arrangement being such that the blocks 81 are normally spaced outwardly with respect to the inner faces of the upwardly extending portions of the margin bars. In the preferred construction, the cells of the rubber at the inner faces of the pressure pads are open. Means is provided for pressing the pads 81 inwardly against the spring action of the brackets 82 so as to engage the side faces of a pile of sheets on the table, such means comprising screws 83 carried by the margin bars with thumb nuts 84 thereon, as is clearly shown in Fig. 2, arranged for forcing the pads inwardly through openings in the vertical portions of the bars 76.

The feed roller 70 and its shaft 71 are preferably arranged so as to be readily removable from the machine. For making this result possible, special types of supporting members for the ends of the shaft 71 are provided (see Fig. 10). At one end, a socket member 85 is slidably mounted within a housing member 86, with a coiled spring 87 engaging the outer end of the socket member for holding it normally pressed inwardly. At the opposite end of the shaft 71, a short shaft 88 is provided mounted in bearings 89 carried by the framework, such shaft extending inwardly beyond the inner face of the side plate 26 and having a pin 90 inserted therethrough. The end of the shaft 71 is bored out so as to have telescopic engagement with the end of the shaft 88, the end of the shaft 71 being notched for operative engagement with the pin 90. Normally the shaft 71 is held in position as shown in Fig. 10 by reason of the pressure of the shaft 71 toward the right by the spring 87. Whenever it is desired to remove the feed roller 70, the shaft 71 is readily moved toward the left in Fig. 10 against the action of the spring 87 for clearing such shaft 71 from the shaft 88 and pin 90.

Immediately in front of the feed roller 70, and at about the same level, two forwarding rollers 91 and 92 are provided in cooperative relation to each other for forwarding to the drum 35 and its cooperating impression roller 56 any sheet presented into their grip. In the construction illustrated, the forwarding roller 91 is rotatably mounted in position by means of a shaft 93 rotatably mounted in position upon a fixed axis by means of bearings 94 at its opposite ends (see Fig. 11). The roller 92 is rotatably mounted in position by means of a shaft 95, the end portions of which are supported by bearings 96 which in turn are mounted in pivotally mounted arms 97 so as to enable the roller 92 to be moved toward and from the roller 91. The arms 97 are extended rearwardly beyond their pivot points, having coiled springs 98 connected with the rear end portions serving normally to hold the roller 92 pressed yieldingly against the roller 91 (see Fig. 7).

Means is provided for applying a film of solvent to the upper forwarding roller 91 for application to each of the copy sheets in turn as

they are moved forwardly by said forwarding rollers. This means comprises a roller 99 rotatably mounted by means of a shaft 100 in the lower ends of arms 101 pivotally mounted by means of machine screws 102 so as to permit the roller 99 to be moved toward and from the forwarding roller 91. Coiled springs 103 serve normally to press the roller 99 yieldingly against the roller 91, as is best shown in Fig. 7.

The means for applying solvent to the roller 91 comprises further a pipe 104 extending across above the rollers 91 and 99 (see Figs. 2 and 4), such pipe being provided with openings 105 in its lower wall portion at intervals across the machine. The pipe 104 is connected by means of a tube 106 with a pump 107 which takes solvent from a receptacle 108 (see Fig. 3) for delivery into the bight of the rollers 91 and 99. In the arrangement shown, a check valve 109 is provided between the pump and the pipe 104. The pump 107 is operated by means of a lever 110 pivotally mounted upon the side plate 25 of the machine so as to be actuated by a second lever 111 pivotally mounted upon the same axis, the lever 111 being provided with a lug 112 engaging the lower face of the lever 110, as is clearly shown in Fig. 3. The lever 111 is given a swinging movement about its pivotal axis by means of a roller 113 rotatably mounted on the lever in position to engage a cam 114 carried by the drum 35. The lever 111 is normally pressed upwardly by a coiled spring 115 interposed between the lever and a lug 116 carried by the side plate 25. The construction is such that the pump 107 is given an operative stroke upon each complete revolution of the drum 35 so as to provide a supply of solvent between the forwarding roller 91 and the cooperating roller 99, as shown in Fig. 4.

In the preferred arrangement, the rollers 56 and 99 are formed of rubber which is somewhat yielding under pressure; the forwarding roller 91 is also made of rubber but somewhat harder and less yielding; the roller 92 is made of sponge rubber with the pores closed at the face of the roller.

For driving the feed roller 70 through the shaft 71 and the connected short shaft 88 intermittently in the direction for forwarding a sheet from the pile 65 to the forwarding rollers 91 and 92, and for driving the forwarding rollers 91 and 92 in the direction for continuing the forward movement of the sheet from the forwarding rollers into the bite of the drum 35 and its cooperating platen roller 56, an operating arm 117 is pivotally mounted upon the framework at the near side of the machine so as to drive the parts in the desired timed relation to each other. This operating arm 117 is pivotally mounted in position by means of a pin 118 (see Fig. 5) which extends into an opening in a heavy supporting plate member 119 removably secured in position on the outer face of the arm 117 by means of screws 120, such screws being mounted in lugs 121 and 122 extending outwardly from the outer face of the side plate 26, as is best shown in Fig. 5. A spring 123 serves normally to hold the arm 117 at the lowermost limit of its swinging motion, as shown in Figs. 1 and 5.

For operating the rollers 70 and 91, the arm 117 is provided with a set of teeth 124 meshing with a pinion 125 loosely mounted upon the short shaft 88, and a set of teeth 126 meshing with a pinion 127 loosely mounted upon the shaft 93 of the roller 91. The pinion 125 is connected with the shaft 88 by means of a one-way

clutch mechanism 128 which is adapted to apply power from the pinion in counterclockwise direction in Fig. 7 for driving the feed roller 70 in the direction for moving the top sheet of the pile of sheets toward the right in Fig. 3, the connections being such that upon an operative stroke of said arm the top sheet is carried into the bite of the rollers 91 and 92 from its normal position as shown in Fig. 3. The clutch mechanism in the arrangement shown comprises a cylindrical part 129 connected with the pinion serving through rollers 130 to drive a head portion 131 which is rigidly connected with the shaft 88. The pinion 127 is connected with the shaft 93 of the roller 91 by a similar one-way driving clutch 132, comprising a cylindrical member 133 connected with the pinion serving through rollers 134 to drive a head 135 connected with said shaft 93.

The arrangement is such that upon a stroke of the arm 117 in clockwise direction in Fig. 5 the pinion 125 is rotated for driving the feed roller 70 in the direction for feeding a sheet from the pile; upon a return stroke of the operating lever 117 in counterclockwise direction in Fig. 5, the pinion 127 is driven for causing rotary movement of the forwarding roller 91 for continuing the movement of the sheet presented thereto by the feed roller 70. Since the roller 92 is pressed continuously toward the roller 91, such roller 92 is caused to rotate at the same surface speed as that of the driven roller 91. The arrangement is such that upon the downward swinging movement of the arm 117 the copy sheet is moved forwardly into the bite of the drum 35 and the cooperating impression roller 56 so as to be thereafter pulled forward by the drum.

The means for actuating the operating arm 117 in timed relation to the rotation of the drum 35 comprises a pinion 136 which is rotatably mounted on the outer face of the side plate 26 of the machine by means of a short trunnion 137 which operates in an anti-friction bearing 138, as is clearly shown in Fig. 12. Upon its outer face, the pinion 136 is provided with a pin 139 in concentric position thereon, which supports a sleeve 140 having a plate 141 formed thereon adjacent to the pinion, with a cam 142 on the outer face of the plate. In the arrangement shown, the sleeve 140, plate 141 and cam 142 are formed integrally with each other. The sleeve 140 is provided on its outer end with a dial 143 (see Fig. 8). Upon the outer end portion of the pin 139, a pointer member 144 is mounted so as to rotate with the pin. On the extreme end portion of the pin 139, a nut 145 is provided, the arrangement being such that the sleeve 140 and the cam 142 can be secured in any desired rotated position with respect to the pinion 136 and pin 139. When the nut 145 is tightened upon the pin, the cam 142 is clamped rigidly into fixed position with respect to the pinion. In the arrangement shown, the dial 143 is graduated so as to have the highest point of the cam positioned directly opposite to the zero of the graduations on the dial.

The means for transmitting power from the cam 142 to the arm 117 comprises a roller 146 rotatably mounted upon the inner face of the arm 117 opposite to the cam 142. The arrangement is such that the roller 146 is kept in engagement with the cam 142 by the pull of the spring 123 on the arm. As will be appreciated from an inspection of Figs. 5 and 5a, when the

pin 139 and the cam 142 are rotated in clockwise direction in Fig. 5 the roller 146 is permitted to stand stationary throughout the major portion of the revolution of the cam, since the cam is circular at the greater part of its periphery. When however the eccentric portion of the cam engages the roller 146, the roller is forced outwardly so as to swing the lever 117 in clockwise direction in Fig. 5 to the position as shown in Fig. 5a. Upon this upward movement of the lever 117, the pinion 125 is actuated by the teeth 124 for driving the feed roller 10. Shortly after the parts have reached the position as shown in Fig. 5a, in the continued rotation of the cam 142 in clockwise direction in said figures, the roller 146 is freed from the high point of the cam, whereupon the spring 123 gives the operating arm 117 a quick motion stroke in counterclockwise direction again into the position as shown in Fig. 5. Upon such quick motion stroke of the arm 117, the pinion 127 is driven in counterclockwise direction in said Fig. 5 by the teeth 126, for giving the forwarding rollers 91 and 92 rotary movement in the direction for moving the then gripped copy sheet quickly toward the right into the bite of the drum 35 and the cooperating impression roller 56. When the copy sheet is gripped between the drum and the impression roller 56, the sheet is pulled forwardly independently of the pinions 125 and 127 and their cooperating means, the clutches 128 and 132 being adapted to yield for permitting such free movement of the sheet.

In the preferred construction, the forwarding rollers and their driving means are arranged so as to carry the copy sheet forwardly sufficiently for causing its leading end portion to be buckled slightly between the forwarding rollers and the platen roller 56 so as to insure that the sheet shall be gripped squarely and evenly by the drum and the platen roller.

As will be readily appreciated, the cam 142 is to be adjusted into such position with respect to the pinion 136 as to cause the feed roller 10 and the forwarding rollers 91 and 92 to operate at the desired interval for assuring that the copy sheet shall move into the bite of the drum and its cooperating platen roller in the desired position with respect to the master sheet 49. Whenever it is desired, the cam can be adjusted for changing the width of the margin at the top of the copy sheet. As the copy sheets are carried forwardly by the drum and impression roller, they pass into position upon a receiving tray 147 removably supported in any suitable manner underneath the drum 35, as shown in Fig. 3.

For showing the number of copies being made by the use of a master sheet, a counter device is provided comprising a dial 148 rotatably mounted on the outer face of the side plate 26, such dial member being provided with ratchet teeth 149 on its periphery. A dog 150 is pivotally mounted upon the arm 117 in position to engage the ratchet teeth 149 at substantially the end of the downward movement of the arm 117, such dog 150 being held yieldingly in operative position by a spring 151. The arrangement is such that upon each return stroke of the lever 117 the dial 148 is given a one step movement. A spring latch 152 is provided so as to engage the ratchet teeth 149 for preventing rotation of the dial in reverse direction.

In the construction illustrated, the pinion 42, by which power is applied to the pinion 40 for rotating the drum, is rotatably mounted upon a

pin 153 extending outwardly from the side plate 26. This pinion 42 is provided on its outer face with a substantially square socket 154 into which the squared hub 155 of a crank 156 extends for rotating the pinion 42, the hub 155 being in the form of a sleeve adapted to slip readily into position upon the pin 153.

The means for rotating the rock shaft 50 against the action of the spring 54 for carrying the fingers 51 out of pressure relationship to the master sheet clamping bar 46, comprises a trip lever 157 pivotally mounted by means of a machine screw 158 secured by means of screw-threads in the side plate 26, as is best shown in Fig. 9. The lever 157 comprises a handle 159 at one end extending outwardly through a notch 160 in the flange 27 of said plate 26. A coiled spring 161 connected with the lever 157 and with the plate 26 serves normally to hold the lever 20 swung outwardly to the limit of its motion as shown in Fig. 1. At the end of the lever opposite from that at which the handle 159 is located a cross bar portion 162 is provided which is adapted to be carried by the lever inwardly and outwardly along a slot 163 in the side plate, as shown clearly in Figs. 1 and 9. The arrangement of the parts is such that when the lever is moved inwardly into the position as shown in Fig. 9 against the action of the spring 161, the cross bar portion 162 is brought into position for engaging the lug 55 carried by the arm 53 mounted upon the shaft 50, as the drum rotates in counterclockwise direction in said Fig. 9. When the lever 157 is held in the position as shown in Fig. 9 and the drum is rotated in counterclockwise direction, the engagement of the lug 55 with the cross bar portion 162 causes the arm 53 to swing in counterclockwise direction for carrying the fingers 51 out of pressure relationship to the flexible bar 46. When thereafter the trip lever 157 is swung again in counterclockwise direction into the position as shown in Fig. 5, the arm 53 is moved back to normal position by the spring 54 for causing the fingers 51 again to press on the bar 46 for holding a master sheet 49 in position on the drum.

In the construction illustrated, means is provided for holding the trip lever 157 in its shifted operative position as shown in Fig. 9. This means comprises a spring pressed detent 164 carried by the end plate 36 of the drum in position to engage a recess 165 in the inner face of the cross bar portion 162 of the trip lever 157. When the parts come into operative engagement as shown in Fig. 9, the detent 164 engages the recess 165 so as to hold the trip lever 157 in turned position against the action of the spring 161 for holding the parts in the position as shown in Fig. 9 with the fingers 51 retracted. After a master sheet has been inserted into operative position in the groove 45 of the drum, the lever 157 can be retracted manually against the holding power of the detent 164 for permitting the spring 54 to return the fingers 51 to their operative pressure positions. If desired, the parts may be released for a return to their normal position as shown in Fig. 1 by a slight rotary movement of the drum 35 for effecting the required movement of the detent 164 with respect to the recess 165.

While the construction and arrangement as above described are preferred, it is to be understood that the invention is not to be limited thereto except so far as the claims may be so limited, it being understood that changes might

well be made in the form and arrangement of parts without departing from the spirit of the invention.

I claim:

1. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield for permitting the feed roller to rotate freely in the same direction when the sheet is moved forwardly independently, and means adapted to drive said forwarding rollers intermittently at substantially increased surface speed as compared with that of said feed roller for continuing the forward movement of said sheet into the grip of said third sheet actuating means and adapted to yield for permitting the forwarding rollers to rotate freely in the same direction when the sheet is pulled forwardly by said third sheet actuating means.

2. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield for permitting the feed roller to rotate freely in the same direction when the sheet is moved forwardly independently, and means adapted to drive said forwarding rollers intermittently at substantially increased surface speed as compared with that of said feed roller for continuing the forward movement of said sheet into the grip of said third sheet actuating means and arranged to overdrive the sheet sufficiently for causing the sheet to be bowed slightly between the forwarding rollers and said third sheet actuating means and adapted to yield for permitting the forwarding rollers to rotate freely in the same direction when the sheet is pulled forwardly by said third sheet actuating means.

3. In a mechanism of the type described, the combination of a frame, a drum rotatably mounted on said frame, means for supporting a pile of sheets adjacent to said drum, means for rotating said drum, a platen roller rotatably mounted in impression relationship to said drum, a feed roller rotatably mounted on said frame so as to engage the top sheet of said pile for feeding the sheet forwardly toward the drum, a pair of forwarding rollers rotatably mounted on said frame adjacent to said feed roller for advancing a sheet from said feed roller into the bite of said drum and its cooperating platen roller, means adapted at a predetermined point in the rotation of said drum to give said feed roller an intermittent ro-

5 tary movement in the direction for forwarding the top sheet into the bite of said forwarding rollers and adapted to yield for permitting the feed roller to rotate freely in the same direction when the sheet is moved forwardly independently, and means adapted shortly after the close of the drive of said feed roller by said intermittently acting driving means to give said forwarding rollers an intermittent rotary movement at 10 substantially increased surface speed as compared with that of said feed roller for continuing the forward movement of said sheet into the bite of said drum and said platen roller and adapted to yield for permitting the forwarding rollers to rotate freely in the same direction when the sheet is pulled forwardly by said drum and platen roller.

4. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield for permitting the feed roller to rotate freely in the same direction when the sheet is moved forwardly independently, means adapted to drive said forwarding rollers intermittently in the direction for continuing the forward movement of said sheet into the grip of said third sheet actuating means and adapted to yield for permitting the forwarding rollers to rotate freely in the same direction when the sheet is pulled forwardly by said third sheet actuating means, an arm swingingly mounted on said frame, gearing connecting said arm with said feed roller driving means and with said forwarding roller driving means adapted upon a stroke of said arm in one direction to drive said feed roller for feeding a sheet from the pile and adapted upon a stroke of the arm in the opposite direction to drive said forwarding rollers for forwarding said sheet to said third sheet actuating means, and means for giving said arm intermittent swinging movements for driving said rollers.

5. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield for permitting the feed roller to rotate freely in the same direction when the sheet is moved forwardly independently, means adapted to drive said forwarding rollers intermittently in the direction for continuing the forward movement of said sheet into the grip of said third sheet actuating means and adapted to yield for permitting the forwarding rollers to rotate freely in the same direction when the sheet is pulled forwardly by said third sheet actuating means, an arm swingingly mounted on said frame, gearing connecting said arm with said feed roller driving means and with said forwarding roller driving means adapted upon a stroke of said arm in one direction to drive said feed roller for feeding a sheet from the pile and adapted upon a stroke of the arm in the opposite direction to drive said forwarding rollers for forwarding said sheet to said third sheet actuating means, and means for giving said arm intermittent swinging movements for driving said rollers.

sheet is pulled forwardly by said third sheet actuating means, a supporting plate removably mounted in position on said frame, an arm swingingly mounted on said supporting plate, means comprising a rotary cam adapted upon each complete revolution of the cam to give said arm a stroke in one direction and a comparatively much more rapid stroke in the opposite direction, and gearing connecting said arm with said feed roller driving means and with said forwarding roller driving means adapted upon the slower stroke of said arm to drive said feed roller for feeding a sheet from the pile and adapted upon the more rapid stroke of the arm to drive said forwarding rollers for forwarding said sheet to said third sheet actuating means.

6. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield for permitting the feed roller to rotate freely in the same direction when the sheet is moved forwardly independently, means adapted to drive said forwarding rollers intermittently in the direction for continuing the forward movement of said sheet into the grip of said third sheet actuating means and adapted to yield for permitting the forwarding rollers to rotate freely in the same direction when the sheet is pulled forwardly by said third sheet actuating means, an arm swingingly mounted on said frame so as to be readily removable therefrom, means comprising a rotary cam and a spring adapted upon each complete revolution of the cam to give said arm a stroke in one direction and a comparatively much more rapid stroke in the opposite direction, and means comprising one-way clutch devices and pinions connecting said arm with said feed roller driving means and with said forwarding roller driving means adapted upon the slower stroke of said arm to drive said feed roller for feeding a sheet from the pile and adapted upon the more rapid stroke of the arm to drive said forwarding rollers for forwarding said sheet to said third sheet actuating means.

7. In a mechanism of the type described, the combination of a frame, a drum rotatably mounted on said frame, means for supporting a pile of sheets adjacent to said drum, a platen roller rotatably mounted in impression relationship to said drum, a feed roller rotatably mounted on said frame so as to engage the top sheet of said pile for feeding a sheet forwardly toward the drum, a pair of forwarding rollers rotatably mounted on said frame adjacent to said feed roller for advancing the sheet from said feed roller into the bite of said drum and its cooperating platen roller, means comprising a cam for driving said feed roller intermittently for forwarding the top sheet into the bite of said forwarding rollers and for driving said forwarding rollers intermittently for continuing the forward movement of said sheet into the bite of said drum and its cooperating platen roller, and means for adjusting the position of said cam for

changing the point in the cycle of movements at which the cam is effective for bringing about the movements of said feed roller and said forwarding rollers.

8. In a mechanism of the type described, the combination of a frame, a drum rotatably mounted on said frame, means for supporting a pile of sheets adjacent to said drum, a platen roller rotatably mounted in impression relationship to said drum, a feed roller rotatably mounted on said frame so as to engage the top sheet of said pile for feeding a sheet forwardly toward the drum, a pair of forwarding rollers rotatably mounted on said frame adjacent to said feed roller for advancing the sheet from said feed roller into the bite of said drum and its cooperating platen roller, means comprising a cam for driving said feed roller intermittently for forwarding the top sheet into the bite of said forwarding rollers and for driving said forwarding rollers intermittently for continuing the forward movement of said sheet into the bite of said drum and its cooperating platen roller, means for adjusting the position of said cam for changing the point in the cycle of movements at which the cam is effective for bringing about the movements of said feed roller and said forwarding rollers, and means connected with said cam and adjustable therewith for showing the position of the cam.

9. In a mechanism of the type described, the combination of a frame, a drum rotatably mounted on said frame, means for supporting a pile of sheets adjacent to said drum, a platen roller rotatably mounted in impression relationship to said drum, a feed roller rotatably mounted on said frame so as to engage the top sheet of said pile for feeding a sheet forwardly toward the drum, a pair of forwarding rollers rotatably mounted on said frame adjacent to said feed roller for advancing the sheet from said feed roller into the bite of said drum and its cooperating platen roller, a pinion connected with said drum so as to rotate concentrically therewith, a second pinion of the same size rotatably mounted on said frame so as to mesh with said first-named pinion, a pin extending from the outer face of said second pinion, a cam rotatably mounted on said pin, a nut secured by means of screw-threads on said pin for clamping said cam in any desired adjusted position with respect to said second pinion, an arm swingingly mounted on said frame in position for engagement by said cam so as to be swung in one direction by the cam, a coiled spring for giving said arm a return swinging movement in the opposite direction, means adapted upon a stroke of said arm in one direction to drive said feed roller in the direction for feeding the top sheet into the bite of said forwarding rollers, and means adapted upon the stroke of the arm in the opposite direction to drive said forwarding rollers in the direction for continuing the forward movement of said sheet for carrying the sheet into the bite of the drum and its cooperating platen roller.

10. In a mechanism of the type described, the combination of a frame, a drum rotatably mounted on said frame, means for rotating said drum, means for pressing a sheet into impression relationship with the drum as the drum rotates so as to cause the sheet to move around with the drum, and forwarding means comprising a roller adapted at a predetermined point in the rotation of said drum to be given an intermittent movement for forwarding a sheet into the grip of the drum and its cooperating impression means

at a considerably higher speed than that at which the surface of the drum moves and adapted to run free after the period of intermittent drive for permitting the sheet to be pulled forwardly independently by the drum.

11. In a mechanism of the type described, the combination of a frame, a drum rotatably mounted on said frame, means for rotating said drum, a platen roller rotatably mounted in impression relationship to said drum, forwarding rollers rotatably mounted in cooperative relation to each other adjacent to said platen roller, an arm swingingly mounted on said frame, means comprising a rotary cam and a spring adapted upon each complete revolution of the cam to give said arm a stroke in one direction and a comparatively much more rapid stroke in the opposite direction, means for giving said cam a complete revolution for each complete revolution of the drum, and means comprising a one-way clutch device and a pinion connecting said arm with one of said forwarding rollers adapted upon the more rapid stroke of said arm to drive said forwarding rollers for forwarding a sheet into the grip of said drum and its cooperating platen roller.

12. In a mechanism of the type described, the combination of a frame, a drum rotatably mounted on said frame, means for rotating said drum, a platen roller rotatably mounted in impression relationship to said drum, forwarding rollers rotatably mounted in cooperative relation to each other adjacent to said platen roller, an arm swingingly mounted on said frame, means comprising a rotary cam and a spring adapted upon each complete revolution of the cam to give said arm a stroke in one direction and a comparatively much more rapid stroke in the opposite direction, means for giving said cam a complete revolution for each complete revolution of the drum, means comprising a one-way clutch device and a pinion connecting said arm with one of said forwarding rollers adapted upon the more rapid stroke of said arm to drive said forwarding rollers for forwarding a sheet into the grip of said drum and its cooperating platen roller, and means for adjusting the position of said cam for changing the point in the revolution of the drum at which the cam is effective for bringing about the movements of said forwarding rollers.

13. In a mechanism of the type described, the combination of a frame, means for supporting a pile of sheets on said frame, a feed roller rotatably mounted on said frame so as to engage the top sheet of said pile for feeding the sheet forwardly, a pair of forwarding rollers rotatably mounted on said frame adjacent to said feed roller for advancing a sheet from said feed roller, a third sheet actuating means adapted by a gripping engagement with a sheet to pull the sheet forwardly edgewise from said forwarding rollers, means adapted to drive said feed roller intermittently in one direction for forwarding the top sheet into the bite of said forwarding rollers and adapted to yield, for permitting the feed roller to rotate freely in the same direction when the sheet is moved forwardly independently,

means adapted to drive said forwarding rollers intermittently in the direction for continuing the forward movement of said sheet into the grip of said third sheet actuating means and adapted to yield for permitting the forwarding rollers to rotate freely in the same direction when the sheet is pulled forwardly by said third sheet actuating means, an arm swingingly mounted on said frame, gearing connecting said arm with said feed roller driving means and with said forwarding roller driving means adapted upon a stroke of said arm in one direction to drive said feed roller for feeding a sheet from the pile and adapted upon a stroke of the arm in the opposite direction to drive said forwarding rollers for forwarding said sheet to said third sheet actuating means, means for giving said arm intermittent swinging movements for driving said rollers, a counter dial rotatably mounted on said frame adjacent to said arm and having ratchet teeth on its periphery, and means comprising a dog mounted on said arm adapted by engagement with said dial to give the dial a single step of movement upon each cycle of movement of said arm.

14. In a mechanism of the type described, the combination of a frame, a table movable upwardly on said frame for supporting a pile of sheets thereon, yielding means normally pressing said table upwardly, a feed roller, supporting members at opposite sides of the table at least one of which is yieldingly mounted so as to be movable transversely away from the other supporting member, means for supporting said feed roller rotatably in position above the table transversely thereof between said supporting members so as to engage the pile of sheets for limiting the upward movement of the table and comprising a shaft on which the roller is mounted and having pin and socket connections with said supporting members, means connecting one of said supporting members with said shaft for causing them normally to rotate together, and means for giving intermittent rotary movements to said last-mentioned supporting member and the connected shaft for causing the feed roller to move the top sheet of said pile forwardly edgewise.

15. In a mechanism of the type described, the combination of a frame, a drum rotatably mounted on said frame, a platen roller rotatably mounted in impression relationship to said drum, means comprising a forwarding roller rotatably mounted on said frame for advancing a copy sheet to said drum and platen roller, a pinion rotatably mounted on said frame, means for driving said pinion in unison with said drum, a pin projecting from the face of said pinion concentrically thereof, a cam member rotatably mounted on said pin, means for clamping said cam fixedly in position on said pin in any desired adjusted position with respect to said pinion, an arm movably mounted on said frame in position to be actuated by said cam, and means actuated by an operative stroke of said arm for driving said forwarding roller.
